UNITED STATES PATENT OFFICE.

CARL W. SWANSON, OF CHICAGO, ILLINOIS.

GEARING FOR WASHING MACHINES.

1,247,175.

Specification of Letters Patent. Patented Nov. 20, 1917.

Application filed May 25, 1916. Serial No. 99,759.

To all whom it may concern:

Be it known that I, CARL W. SWANSON, a citizen of the United States, residing at Chicago, in the county of Cook and State of Illinois, have invented certain new and useful Improvements in Gearing for Washing-Machines, of which the following is a specification.

My invention relates to improvements in 10 gearing for washing machines, and more particularly to means for operating an oscillating-tub washing machine.

Among the objects of my invention are to provide a construction, advantageously 15 adapted for power actuation of the washing machine tub; wherein the mechanism is constructed to oscillate the tub without damaging shocks or jars, and with minimum power loss, and is capable of ready operation 20 to connect or disconnect the tub with respect to the constantly running parts.

Further objects of my invention are to provide a construction which is simple, inexpensive, durable, efficient, not liable to get 25 out of order, easily manufactured, and readily cared for and maintained by inexperienced persons.

In the drawings

Figure 1 is a front elevation of a washing machine embodying my invention;

Fig. 2 is an end elevation thereof, from the left hand end of Fig. 1;

Fig. 3 is an end elevation, from the right end of Fig. 1;

Fig. 4 is a perspective detail of a tub-connected crank;

Fig. 5 is a section on line 5—5 of Fig. 3;

Fig. 6 is a horizontal section on line 6—6 of Fig. 3;

Fig. 7 is a vertical section on line 7—7 of Fig. 6.

Fig. 8 and Fig. 9 are perspective details of parts shown in Fig. 7.

The oscillatable washing machine tub 10 is pivotally supported in a frame structure

11. The tub is preferably a sheet-metal, top-opening receptacle having at its ends bracing spiders 12, from which project the pintles 13 and 14 that find suitable bearing 15 in the frame and on which the tub oscillates.

Each side member 16 and 16' of the frame preferably has two leg pieces 17 connected by a cross bar, 18 or 18', a vertically extending, nearly central bearing upright 19 in 55 which the bearing for the tub pinte is arranged, and a top extension 20 back of the

upright 19. A longitudinal frame member 21 above the tub connects the extensions 20, and two longitudinal bars 22 below the tub connect the end members, 18, 18' of the 60 frame.

A suitable source of power, such as the electric motor 25, that is mounted on a pedestal 26 secured to the lower front portion of the frame, drives, through a belt 27, 65 a power wheel 28 that is mounted on a short power shaft 29, disposed in a long bearing 30 that is carried by or formed integrally with the frame bar 18' and that preferably has a large oil-receptacle 30' formed there- 70 in. This power shaft 29 carries an elongated driving pinion 32 that constantly meshes with an axially-shiftable gear 33 slidably mounted on a shaft 34 that, for identification I term the main shaft and that 75 is arranged near the rear of the machine to find bearing in the frame bars 18 and 18'. The main shaft bearings may have oil ducts 34'. The axially shiftable gear 33 is moved by a shifter yoke 35 engaging in a 80 peripheral slot 36 in the gear hub, said yoke being carried by a sliding shaft 37 that extends through a suitable bearing 38 in the frame member 18' and is axially reciprocable by a shifter lever 40 that is pivoted, as at 85 41, on projections 42 on the frame member 18', and that extends up the side of the frame for convenient access.

In either of the positions to which the gear 33 may be shifted by the lever 40 it 90 engages the elongated pinion 32, but in its inward position, to which it may be thrown by outward movement of the lever 40, said gear makes rotative connection with the main shaft 34, while in its other position it 95 is disconnected from the shaft 34. To this end the hub-part 44 of the gear 33 is formed with positive clutch studs or heavy teeth 45 that may engage with or disengage from complementary teeth 46 of a clutch-member 100 47 fast on shaft 34.

When driving connection between the gear 33 and shaft 34 is established, and the shaft 34 is thereby rotated, oscillating motion is imparted to the tub 10. At its extremity beyond the frame member 18, the shaft 34 carries a crank 50 secured thereon, and the extremity of this shaft-crank is connected by link 51 with a tub-crank element 52 that is loose on the pinte 14 of the tub. 110 As best shown in Figs. 4 and 5 the tub-crank 52 is preferably bifurcated and its two limbs

52^a and 52^b straddle the upright frame-part 19 to engage the pintle on both sides of its bearing. The tub-crank has a transverse head 52^c that extends through an opening in the frame to receive the pivoted end of link 51, and it is also provided with a horizontally disposed extension-lug 54 that extends into proximity to the end of the tub. This lug has a slot 55 through which extends a vertical pin 56 that is fixed at opposite ends in brackets 57 carried by the bracing spider 12', and springs 58-58 coiled around said rod 56 form a resilient or shock-absorbing connection between the crank and the tub.

It will be appreciated that the operation of the power devices is subject to peculiarities due to the nature of the machine in general. The washing machine body contains a heavy weight of water and clothing, which is violently thrown from side to side of the tub owing to the oscillation of the latter, but which does not perfectly synchronize with the tub movement. With an empty tub, only tub-momentum must be overcome, but with the mass of clothes and water being thrown violently from side to side, not in perfect time with the mechanical reversals of tub-movement, the shocks tend to rack the power mechanism badly. The yielding connection afforded between the tub operating crank 52 and the tub proper gives a very advantageous shock-absorber action, permitting the movements of the tub, influenced in part by the load-movements, to accommodate themselves to the positively-timed crank movements with minimum shock or drag. Thus the tub may lag somewhat behind the reversing action of the crank 52 at the end of its oscillatory movement, and then, (since one of the springs 58 is compressed owing to the lag action of the tub) the tub movement may be accelerated through the spring expansion after the tub has started its reverse action, and the tub may even lead the crank, by compressing the other spring. Thus the machine may be run at high speed and gets a snappy action of the tub that is very effective in easing each tub-reversal and then snappily starting the water and clothes back toward the opposite side of the tub, in addition to minimizing the shocks, that would fall heavily upon the power appliances were direct, positive connection made between the crank 52 and the tub.

Since, in the construction shown, the cranks 50 and 52 are both approximately horizontal when the tub is in mid-position of its oscillatory movement, the maximum shiftable weight of the load within the tub is thrown on the descending side of the tub just after cranks 50 and 52 pass mid-position, and of course such load-shift tends strongly to accelerate the movement of the

shaft-crank 50. To prevent irregular action of the machine due to this cause and also to assist in carrying the shaft-crank 50 over the point at which the tub movement is reversed, I provide means coöperating with power shaft 34 to resist somewhat its movement during the time that shaft crank 50 is approaching this point of reversal and to assist its movement to carry the crank past the reversal point. In the drawings 60 indicates a two point cam mounted on shaft 34 approximately parallel to crank 50 and co-operating with a metal strap 61. The strap is pivoted to the frame member 18, at 62, and is formed in a suitable curve, intersecting the path of the cam 60. At its end a slotted portion 62' thereof is guided on a pin 63 mounted in suitable brackets on the frame member 18 and said pin is surrounded by springs 64-64 acting oppositely against the ear 62'. As either point of the cam 60 descends its movement from mid-position toward the nearest vertical point is increasingly resisted by the braking action of the band 61, and then, after the acting point of the cam passes the part of the pivoted band 61 that is closest to the shaft 34, the lower spring 64 reacting on said band 61 tends to force the point past the vertical as the band is being spring-restored to normal position.

Cooperatively, therefore, as well as individually, the shock-absorbing structures associated with both cranks 50 and 52, act to stabilize the load on the motor 25, and enable power-loss to be avoided.

In addition to its stated relation to the clutch member 47, by which it may either drive or release the shaft 34, the slidable gear 33 has a constant driving relation to a fixed gear 70. Such driving but slidable relation is maintained through the constant engagement of the slotted hub extension 71 of the gear 33 with lugs 72 on the gear 70 that is rotatable upon but axially fixed with respect to the shaft 34. This non-slidable gear 70 is beveled and coöperates with a horizontally disposed beveled gear 73 carried by a vertical shaft 74 which extends up through suitable brackets 75 and 76 associated with the cross bar 18' and the top bar 21 of the frame, to apply driving power to a wringer. Through mechanism, which I do not here specifically claim, (as it is to be made the subject matter of another patent application) the wringer is made bodily rotatable about a vertical axis and yet reversible in operation. Specifically the bearing 76 has a fixed top plate 78 peripherally notched, as at 79. The wringer 80 is mounted in a wringer-frame 81 that comprises a horizontal bar 82 having a bearing sleeve 83 extending through the bracket 76 and surrounding the shaft 74, and having beyond said bearing sleeve a bracket arrangement 84 that extends upwardly and in-

wardly to terminate in a head 85 located directly above the shaft 74. In this bracket 84 is mounted a horizontal shaft 87 which is coupled as at 88 with the main shaft of the wringer. Shaft 74 bears a beveled gear 90 that constantly meshes with two beveled gears 91 and 92 loose on shaft 87, these gears, of course, rotating oppositely. Either such gear 91 or 92 may be clutched to shaft 87 by a shiftable clutch member 94, slideable on but rotatively fixed to the shaft 87 and arranged to coöperate with the coacting clutch teeth on either gear 91 or 92 accordingly as the shiftable clutch member 94 is shifted by a lever 95 that is pivoted on the head 85. The wringer frame as a whole may be rotated about the shaft 74 at its center, the gears 91 and 92 traveling planet-fashion about the gear 90, and the frame 20 may be latched in any of its desired positions by a latch lever 97 pivoted to the lower bar of frame 81 and adapted to engage in any one of the notches 79 of the bearing plate 78. Of course when the clutch member 25 94 is in mid-position, as shown in Fig. 1, the shaft 74 rotates idly, but the wringer may be thrown into instant operation, to be run forwardly or reversely, by mere manipulation of the lever 95, no operation of 30 the main clutch member 40 being necessary to control the wringer operation, as the wringer may be worked whether the tub is in oscillation or not.

While I have herein described in some detail a particular embodiment of my invention, it will be understood by those skilled in the art that many changes may be made therein without departure from the spirit of the invention and within the scope of the 40 appended claims.

Having described my invention, what I claim is:

1. In a driving gear for an oscillating hollow container adapted to receive a liquid mass to be violently agitated, the combination of a rotatable shaft, a shaft-crank thereon, a container-crank for connection with the container, a link connection, for oscillating the container crank as the shaft crank 45 rotates, positioning said cranks approximately horizontal in mid-throw, and means, coacting with said parts, to brake the action thereof as the shaft-crank is approaching a vertical position and to assist said shaft 50 crank in passing vertical position.

2. In a driving gear for an oscillating washing machine, the combination of a rotatable shaft, a shaft-crank thereon, a tub-crank for connection with the washing machine tub, a link connection, for oscillating the tub crank as the shaft crank rotates, positioning said cranks approximately horizontal in mid-throw, and means, coacting with said parts, to brake the action thereof as the shaft-crank is approaching either

of its vertical positions and to assist said shaft crank in passing vertical position.

3. In a driving gear for an oscillating washing machine, the combination of a rotatable shaft, a shaft-crank thereon, a tub-crank for connection with the washing machine tub, a link connection, for oscillating the tub crank as the shaft crank rotates, positioning said cranks approximately horizontal in mid-throw, and means, coacting with said parts, to brake the action thereof as the shaft-crank is approaching either of its vertical positions and to assist said shaft crank in passing vertical position, said means comprising a double pointed cam on 70 the shaft and a coöperating strap pivoted at one end and spring sustained at its other end.

4. Power mechanism for an oscillating washing machine comprising, in combination with the oscillatable tub, the frame, and the power shaft 34, a tub crank 52, a shaft crank 50, connecting link 51, double pointed cam 60 on the shaft 34 and coöperating strap 61, spring sustained at one end and 85 acting to brake the movement of cam 60 as crank 50 passes through a quadrant approaching the point at which the tub movement is reversed, and to propel cam 60 as said crank 50 is passing said point of tub 90 reversal.

5. The combination with a washing machine frame and an oscillatable tub mounted therein, of means to power operate said tub including a crank mounted co-axially with 100 the tub, means to drive said crank, and connection between said crank and the tub comprising projecting lugs carried by the tub end above and below the crank end, a rod fixed in said lugs and extending through an 105 opening in the crank end, and springs interposed between both of said lugs and the crank end and surrounding said rod.

6. The combination with a washing machine frame and a tub mounted therein for 110 oscillation, of a bracing spider secured to the end of the tub carrying the tub-bearing pintles and bearing upper and lower lugs, a crank on one of said pintles projecting between said lugs and having an opening in its 115 end, a rod mounted in said lugs extending through said opening, springs interposed between said lugs and the end of the crank, and means to oscillate the crank.

7. In a washing machine power-installation, the combination with a tub having a pintle and a frame having an upright bearing member in which the tub pintle is mounted for oscillation, of lugs mounted upon the tub ends, a bifurcated crank straddling the frame upright and mounted loosely on the tub pintle, said crank having an extension formed with an opening lying in alinement with and between said lugs, a rod connecting said lugs extending 120 125 130

through the lever opening, springs interposed between said lugs and the crank, and means to oscillate said lever.

8. A power installation for a combined oscillating washing machine and rotary wringer, comprising, in combination with the frame, the wringer mounted in the upper portion thereof, and the oscillatory tub mounted below the wringer, a rotatable power shaft, means to impart constantly rotation thereto, a main shaft, driving connections between said main shaft and the tub, an elongated pinion on the power shaft, an axially shiftable gear on the main shaft, in constant mesh relation with said pinion, clutch connection for engaging said shiftable gear in driving relation with the main shaft in one of its positions and freeing it therefrom in its other position, a vertical shaft, means to connect it in the power supplying relation to the wringer, coacting gears in constantly meshed relation on the vertical shaft and main shaft, the main shaft gear being rotatable on its shaft, and

a slidable connection constantly maintaining 25 driving relation between the two gears on the main shaft.

9. In an oscillating-tub washing machine the combination of a tub, a frame therefor, a driving means, a main shaft, connections 30 between the main shaft and the tub including a main-shaft-crank and a link, said connections including a yielding element between the main shaft and the tub permitting lagging of tub-reversal behind the reversal 35 of crank-direction, and means acting on the main shaft automatically to brake its approach to the point of reversal of tub movement and to assist its passage beyond said point of tub reversal. 40

In testimony whereof I hereunto set my hand in the presence of two subscribing witnesses.

CARL W. SWANSON.

In the presence of—

STANLEY W. COOK,

MARY Y. ALLEN.
